UNITED STATES PATENT OFFICE

JOSEPH SZINAY, OF NEW YORK, N. Y.

FOUNTAIN-FEED DRAWING PEN

Application filed October 15, 1928. Serial No. 312,413.

This invention relates to a fountain-feed drawing pen and its object is to provide an article of this character having a reservoir and a novel feed mechanism which may be 5 actuated by the user to cause a flow of ink from the said reservoir to a distributor blade and thence to the nibs of the pen.

A further object is the provision of a valve retaining sleeve in which the working parts 10 of the said valve are assembled and which also serves as a connecting element for the attachment of the barrel, or handle of the pen and the nib members thereof.

These and other objects and features of 15 the invention will be fully described in the following specification and claims and illustrated in the accompanying drawings, in which:

Fig. 1 shows a side view of the pen.
20 Fig. 2 shows a front view of same.

Fig. 3 shows, on an enlarged scale, a section on the line 3—3 of figure 1.

Fig. 4 shows, also enlarged, a section on the line 4—4 of figure 3.

25 Fig. 5 shows a plan view of the valve seat removed from the casing.

Referring first to figures 1 and 2 of the drawings; the principle elements of the pen are as follows:

30 The valve sleeve 10, the barrel 11 and the nibs 12. The barrel has a screw cap 13 for filling and the nibs have the usual thumb adjusting screw 14. In operation; ink is released onto the distributor blade 15 by pressing on the button 16 the action of which will be described later.

Now, referring to figures 3, 4 and 5 of the drawings; it will be seen that the valve seat 35 17 is screwed into the sleeve 10 coming to rest at the point 18. It has a boss on its lower face which fits into a recess in the rotatable valve disk 19, the said recess being indicated by the dotted line 20.

40 The disk 19 is secured by the bolt 21 which has a nut 22 thereon and a screw head 23

at its lower extremity. A spring 24 maintains a suitable pressure on the valve disk. An elongated hole, or duct 25 passes through the valve seat and permits the ink to flow from the reservoir 26 when the hole 27 of the 50 valve disk is in open alignment.

Secured to the disk 19 in the manner illustrated in figure 4, is the push-rod 28 which, being held by the screw pin 29 passes through the slot indicated by the dotted lines 30 and 55 through the spring clip 31 terminating in the button 16. A supplementary spring 32 augments the action of this rod.

When the ducts are closed, as is the case when the rod is fully out; the hole 27 rests 60 at a point in advance of the hole 25. The elongated shape of the hole 25 as seen in figure 5, permits of a flow of ink for a longer period when the button is pressed than would be the case if it were simply round as the 65 hole 27. The holes 33 indicated in the valve seat pass only partly through the same and are for aid in assembling; a spanner being used for the purpose.

The nibs 12 are secured to the plug 34 70 together with the distributor blade 15. This plug is screwed into the sleeve 10 and leaves clearance for the rotating of the valve disk 19.

While the device is shown and described in its preferred form; it is understood that 75 such minor changes may be made therein as may come within the spirit and scope of the appended claims.

Having thus described my invention, what I claim as new and desire to secure by Letters 80 Patent, is as follows:

A reservoir valve comprising a seat within a sleeve and the said seat having a downwardly disposed boss thereon, a rotatable disk recessed to fit over the said boss and 85 secured in position thereon by means of a central bolt and a tension spring which bears against the bolt head and the base of the said disk, an elongated hole in the seat element and a perforation in the rotatable disk 90

which is adapted to be brought into alignment with the said elongated hole when actuated by a push rod which is pivotally attached to the said disk at an off center point of same and which rod is retractable by means of a spring located between the outer wall of the said sleeve and a button head on the said push rod.

Signed at New York in the county of New York and State of New York this 22nd day
10 of September A. D. 1928.

JOSEPH SZINAY.
